UNITED STATES PATENT OFFICE

168,327

COMBINED TRAY AND CUP OR SIMILAR ARTICLE

James B. Alper, New York, N. Y.

Application August 13, 1951, Serial No. 16,256

Term of patent 14 years

(Cl. D44—10)

To all whom it may concern:

Be it known that I, James B. Alper, a citizen of United States, residing in the city of New York, Borough of Manhattan, county and State of New York, have invented a new, original, and ornamental Design for a Combined Tray and Cup or Similar Article, of which the following is a specification, reference being had to the accompanying drawing, constituting a part hereof:

Fig. 1 is a top plan view of a combined tray and cup or similar article, showing my new design;

Fig. 2 is a cross-sectional view taken on line 2—2 of Fig. 1; and

Fig. 3 is a side elevational view thereof.

I claim:

The ornamental design for a combined tray and cup or similar article, substantially as shown.
JAMES B. ALPER.
